UNITED STATES PATENT OFFICE

2,557,104

HOLLOW SPINNING OR TWISTING MEMBER

Ede Hegediis, Budapest, Hungary

Application January 7, 1948, Serial No. 991
In Hungary September 9, 1943Section 1, Public Law 690, August 8, 1946
Patent expires September 9, 1963

18 Claims. (Cl. 57—128)

1

The present application covers improvements in and relating to twisting devices for temporary twisting, twisting members adapted for use therewith and spinning or twisting machines equipped with such twisting devices.

There are several uses in the spinning and twisting industries for twisting devices adapted to give a twistable material, such as a single, or cabled yarn or thread passing through them, a temporary or false twist. It is obviously important with any of such devices that the threading-in should be accomplished with a minimum amount of time. The twisting devices or false twisters heretofore known were however not satisfactory from this point of view, as even in the most improved devices the twister head had to be taken out or the whole device stopped in a prescribed position in order to render possible the threading-in of the yarn.

The present invention is based upon the astonishing discovery that the yarn can be introduced laterally into a properly designed twisting device while the twisting member or twister head is running at full speed in such manner that the yarn is brought automatically into its twisting position and does not leave this position during the twisting operation, so that the threading-in into the new false twister in accordance with the invention does not require substantially more time than the insertion of the yarn into an ordinary thread-guide on a ring-frame.

Accordingly, the principal object of the present invention is a twisting device comprising a twisting member provided with a lateral slit, bearing means for said twisting member having at least one laterally open section, and driving means located in such a manner as to leave free the passage through the said open section of the bearing of the twisting member, wherein the surfaces of the bearing means and those of the slit of the twisting member form a passage through which the twistable material is introduced laterally during the rotation of the twisting member, while the outer surface of the twisting member is designed in such a manner that only the lateral slit is adapted to take with the twistable material in the prescribed direction of rotation of the twisting member, so that the twistable material can be introduced into the rotating twisting member, laterally, at any point of its length, and without threading in the end of a yarn.

The mechanical requirements that two guiding surfaces rotating relatively one to another form a free passage for a yarn moving in a certain direction, and that the yarn should not become

2

wedged between these rotating surfaces, and should not get cut or broken in consequence thereof, can be derived from the laws of mechanics relating to friction. Accordingly a knowledge of 5 the present invention as hereinafter particularly described enables those skilled in the art to design such surfaces without difficulty. The technical achievement and effect attained by the invention, however, is new and surprising because, 10 with regard to the great number of the twisting devices heretofore known and proposed, and to the fact that none of these devices has been adapted for threading in during the rotation, it was not to be foreseen that with a proper design of the twisting device a cotton yarn having 15 a very little tensile strength could smoothly enter the slit of the twisting member rotating at a speed of 10,000 revolutions per minute, the said slit having a width of but a few tenths of a millimeter.

The twisting device according to the invention 20 differs fundamentally from the previously known twisting devices whose twisting heads and bearings are provided with narrow slots which can be 25 brought into alignment to render possible the lateral insertion of the yarn into the previously stopped twister head through the said slots, because the contacting edges of the slots arranged in this manner would act as a pair of scissors and cut the yarn if it came between them during 30 the rotation of the twisting member.

The yarn brought into contact with the surface of the twisting member through the open section of the bearing can jump into a slit even 35 if it is parallel to the axis of rotation of the twisting member. The introduction of the yarn, however, is rendered smoother and easier when the slit is arranged obliquely in such a manner that the yarn, lagging with reference to the rotating twisting member, is caused by this lagging 40 to slip into the slit and through the said slit inwardly in a direction towards its twisting position. For this purpose the slit may be arranged obliquely both axially and radially. It is suitable 45 and promotes the threading in, when the angle of inclination of the slit is unchanging throughout its length, though a slit following an undulating course not exceeding a certain limit does not hinder the threading in during the rotation. It is particularly simple and very advantageous solution to arrange the slit in a plane 50 forming a suitable angle with the axis.

According to an advantageous embodiment of 55 the invention the relative position of the slit and the members in frictional engagement with

the yarn, is designed in such a manner that the slipping out of the yarn through the said slit is prevented by these parts without the provision of closing means for the slit.

In certain cases it is sufficient for this purpose to arrange the slit obliquely as hereinbefore already mentioned in connection with the introduction of the yarn.

In a preferred embodiment of the twister head or twisting member adapted to be used in the false twister according to the present invention, yarn engaging members are provided which are in frictional engagement with the twistable material, and impart the friction necessary for twisting. Guiding surfaces are also provided to lead the said twistable material into its twisting position on the said yarn engaging members during and in consequence of the rotation of the twisting member and under the influence of the lateral components of the external forces acting upon the said twistable material during the threading-in as well as of the inertia of the twistable material. The said yarn engaging members and the guiding surfaces leading to them from the slit of the twisting member are constructed and arranged so as to prevent any substantial outward displacement of the twistable material.

These and other features of the invention will be best understood and appreciated from the following description of some preferred embodiments thereof, selected for purposes of illustration and shown in the accompanying drawings in which

Fig. 1 is a sectional elevation of one embodiment of the invention taken on line I—I of Fig. 2.

Fig. 2 is a view of the same from below.

Fig. 3 is a top plan view of one embodiment of the twisting member.

Fig. 4 is a sectional elevation of the same according to line IV—IV of Fig. 3.

Fig. 5 is a sectional elevation view of another embodiment of the twisting member and the twisting device, taken in line V—V of Fig. 6.

Fig. 6 is a top plan view of the same.

Fig. 7 is a longitudinal section of a detail of the twisting member according to Fig. 5 on a still larger scale.

Figs. 8, 9 and 10 represent another constructional form of the twisting member, Fig. 8 being a side elevation, Fig. 9 an end view and Fig. 10 a view in perspective of the twisting member in a very enlarged scale.

Fig. 11 is a diagrammatical illustration of a preferred use of the twisting device.

The twisting member 11 provided with a lateral slit 20 is supported floating between the rollers 12, 13 and 14. It is prevented from falling out by flanges 28 which are also intersected by the slit 20. The rollers 12, 13 and 14 are mounted on the support 15 which is pivoted to the plate 18 by the hinge 16 said plate 18 being secured to some part of a machine frame 19. The support is held yieldingly in its operative position by the cam arrangement 17.

The roller 12 is rotatably supported by the arm 31 which can swing about the pivot 30. The spring 32 urges the arm 31 inward, in such a manner that the twisting member is yieldingly pressed by the roller 12 into engagement with the rollers 13 and 14. The mounting of the roller 12 on the pivoted arm 31 renders possible the removal of the twisting member simply by pulling it from between the rollers, and also the use of twisting members of different sizes in the same device. According to the embodiment as

shown, the twisting member is driven by means of the roller 14 which latter may be operated, as shown in Fig. 11, by means of a friction wheel 34 secured to the shaft 35.

Through the broad opening of the support 15 between the rollers, the yarn or the like may be brought into contact with the surface of the twisting member 11. The yarn touching the periphery of the twisting member is then caught by the forward end of the slit 20 and enters through this slit into the twisting member. As is apparent from Figures 1 and 2 the yarn entering the slit of the twisting member at one of the flanges 28 can not get jammed owing to the fact that it can come into contact with the surface of one of the rollers (e. g. roller 13); on the contrary the surface of the roller, acting as an inclined plane, pushes the yarn forward into the slit. It does not cause a jamming of the yarn either when the yarn comes by chance between the roller and the twisting member, because the contact of the roller and of the twisting member is yielding, so that the yarn can pass between them. By reason of the play or "give" thus provided between the twisting member and the means by which it is supported, the material being twisted can pass between the supporting means and the twisting member without being sheared.

The slit 20 of the twisting member, associated with guiding passages 21 and 22 at its ends, according to the embodiment herein shown, is arranged in a plane oblique to the axis of rotation. The arrangement of the said plane is such that the yarn entering at the opening of the passage 22 and lagging with reference to the rotating twisting member is caused by the rotation of the twisting member to travel inwardly through the slit and the guiding passages 21 and 22, towards its twisting position.

The parts of the twisting member which are in frictional engagement with the yarn are formed according to a preferred embodiment of the invention by preferably central eyelets at both ends of the twisting member and by a further guide member arranged in such a manner that their yarn engaging points are not in one straight line, and they guide the yarn in an undulating line.

This design and arrangement of the parts in frictional engagement with the yarn is advantageous from the point of view of the invention, as the guiding of the yarn into its undulating position in the eyelets and on the guide member is very simple. In Figs. 1 to 4 the eyelets are shown as consisting of central bores 24 and 25 in the end plates of the twisting member, and the further guide member as a rod 26 extending transversely of the twisting member. The radial distance of the yarn engaging surface of the guide rod 26 from the axis of the twisting member is greater than the radius of the central bores so that the yarn is forced to travel an undulating path.

In order to reduce the longitudinal frictional resistance of the yarn and to diminish the wear of it, the edges of the means 24, 25, 26 coming into contact with the yarn are preferably rounded off. For this purpose the guide member 26 may have a surface of rotation and in Figs. 1 to 4 it is shown as a cylindrical bolt.

The passage 22 lying ahead of the other passage and arranged at the output end of the twisting member is substantially straight and opens laterally into the eyelet from a tangential

position, in order to render it more difficult for the yarn to slip out of the eyelet into the passage. The passage arranged at the entrance side of the twisting member and lying further back with reference to the direction of rotation, leads first into the opening 23, and changing its direction at about 180° opens into the upper eyelet 24. The directions in which the yarn passes from the two passages into the two eyelets, form accordingly an angle of about 270° , making thus more difficult a substantial displacement of the yarn from its twisting position.

As shown in Fig. 11, at the lower side of the twisting member the ballooning of the yarn takes place, where the yarn is gyrating substantially at the same rate as the twisting member. Accordingly at this side the direction of the lateral component of the yarn stress does not vary at a greater degree relatively to the twisting member during one revolution of the same. Consequently the yarn guiding path on this side does not bend considerably either. The course of the yarn in this path has its only sudden change of direction at the point where the yarn jumps laterally into the eyelet 25. On the contrary, at the upper side, the yarn held obliquely to the axis of rotation makes a full revolution relatively to the twisting member during each revolution thereof and during the revolution of the twisting member the stress acting upon the yarn at this side will have a component coinciding with the longitudinal direction of the passage at any point of the latter even in that case when the passage bends with an arc of 180° or more, in a sense opposite to that of the rotation. A passage bent in such a high degree may render considerably difficult a substantial displacement of the yarn from its twisting position in cooperation with a less bent or substantially straight guiding path meeting the corresponding eyelet from a different direction.

In the end surface of the twisting member 11 a further large opening 23a is formed besides the large opening 23 as shown in Figs. 2 to 4. The said openings serve together with the openings possibly arranged also in the wall surfaces of the twisting member as in Fig. 10 to let the waste or ooze to fly out, which could otherwise fill up the twisting member, rendering thus impossible the threading in during rotation, and could cause yarn breakage too.

A curved rod 35 may also be arranged on the twisting device if it is desirable to damp the vibrations of the yarn entering the twisting member.

In case of the embodiment shown in Figs. 1 to 4, the twisting member is provided with flanges at both ends, embracing the rollers. It may be, however, sufficient to provide a flange only at the upper end, to prevent the twisting member from falling out, as the force acting upon it has generally always the same downward direction.

According to Figs. 5 and 6 the axial displacement of the twisting member is hindered by flanges provided on the rollers.

According to this form, the twisting member is supported by the rollers, 54, 55, 56 which may be arranged substantially in the same manner as the rollers 12, 13 and 14. In this case the twisting member consists of the end plates 51 and 53 and of the sheet metal ring 52 snapped into the preferably outwardly inclined grooves 57 and 58 in the said plates. The slit or gap 59 is bounded by the oblique edges of the sheet metal ring and opens into the passages 62 and 63 formed in the end plates 51 and 52 and leading to the central openings 60 and 61. The grooves 57 and 58 are 75

interrupted at one or more points 64 and 65 respectively, and the sheet metal ring is cut away at corresponding places for insuring coincidence of the guiding elements 59, 62 and 63.

In case of the constructional forms according to the previous figures the rod forming the lateral guide member has been arranged in a stationary manner. In order to avoid the inconvenience that the yarn may cut in the guide member, the rod, bolt or shaft may be arranged in such a manner that it can be turned, e. g. by means of a tool, or, as shown in Figs. 5 and 7, it rotates continuously with the longitudinal movement of the yarn. The rotatable guide member may have the advantage that not only a cutting in is avoided but also the axial resistance of the yarn is limited to a value which corresponds to the force necessary to rotate the shaft or bolt. The circumferential friction which is important from the view of point of twisting remains hereby unchanged and may be even increased by the concave design of the bolt or shaft as shown in Fig. 10.

In the constructional form, according to Figs. 5 and 7 the pointed ends 68 of the guide bolt 25 66 are rotatably supported by the bearing like ends of the casing 67, the latter being provided with a recess in the middle in order to insure the free passage of the yarn. Through this arrangement it is rendered more difficult for dust or ooze to get deposited in the bearings of the shaft or bolt 66.

The openings and other elements having a ventilating effect as mentioned above, may be used also in connection with the last mentioned constructional form of the twisting member. Besides that, the upper end surface 51 of the twisting member may be made for example convex so that the dust and fiber fragments settling on this surface can easily fly off again. The said surface 51 may be provided also with radial grooves 51a to assist in keeping it clean by means of a radial current of air set up through the action of the grooves as wheel blades.

Figures 8 to 10 show another construction of the twisting member. At the ends of the said twisting member having an outer surface of the body or wall portion shaped to form a surface of revolution and provided with flanges 80 and 81 at both ends, furthermore with a lateral slit 82, there are arranged elongated guide members 83 and 84, formed for example of steel wire, extending from the periphery of the twisting member towards its axis. The inner free ends of the guide members 83 and 84 are bent to form ring-shaped eyelets (centralizing members) 85 and 86 respectively. The said guide members 83 and 84 are tapered toward their free ends 87 and 88, which are made to bend over the stem, so as to form substantially closed centralizing eyelets or rings. As is herein shown, the entrance openings of both of the eyelets formed by the turned back end portions of the wire member lie with reference to the direction of rotation on the same side of the corresponding wire stem. The members 83 and 84 are placed on one side of the slit 82, while the third guiding member 89 which, according to Fig. 10 is shaped as a bolt, is located on the other side of the slit, which latter side lies in front in the direction of rotation indicated by the arrow on Fig. 10. In order to increase the surface engaging the yarn circumferentially, a concave part, formed as a groove 90 is provided in the bolt 89, assisting at the same time to keep the yarn in its central position. The slit 82 is widened at its end 91 lying in front in the direction of ro-

tation. This is instrumental in facilitating the slipping in of the yarn or thread into the slit of the rotating member.

In the body or wall portion of the twisting member there are openings 92 and 93, adapted to cause a current of air through the twisting member in order to remove dust or fiber fragments from the interior of the member.

According to the embodiments hitherto described the twisting member has been prevented from falling out from its bearings by means of flanges. The invention is, however, by no means limited to the use of flanges, as the axial displacement of the twisting member is, of course, always prevented if all or some of the surfaces of the bearing or bearings and those of the twisting member are not cylindrical bodies of rotation. For example when the surface of the twisting member is spherical, the axis of the twisting member may assume its most favorable position automatically.

In the forms of the invention as above described, the twisting member is supported by three rollers. Although this construction has many advantages, particularly in case of the frictional drive of the twisting member, the invention is not limited to this specific arrangement. The basic requirement is that the bearing does not entirely surround the twisting member but has an open section having the characteristics set forth in the present specification and claims.

The invention is similarly not limited to the particular kind of drive herein shown although this drive is highly advantageous. Any other drive may also be used in connection with the invention, which leaves the open section through the bearing unobstructed.

Instead of using a mechanical drive, the twisting member may be driven by means of a current of air or other driving fluid or may be driven electromagnetically, for example as shown and described in my co-pending application Serial No. 82,986.

In the spinning or twisting machine according to Fig. 11 the twistable material coming from the drafting rollers, and passing perhaps over the vibration damping bar 33, enters the twisting member 11 which gives a "temporary" or "false" twist having the same direction as the twist given by the spindle 37 to the twistable material between the front rollers and itself, thereby increasing its strength substantially. The yarn leaving the twisting member is wound up on the bobbin on the spindle after having passed the traveller revolving upon the ring 38. The twisting member 11 is driven by the roller 14, operated by the friction wheel 34 mounted on the shaft 35. The shaft 35 may drive at the same time several twisting devices. When the support 15 is pivoted upwardly around the hinge 16, the driving engagement is broken between the friction wheel, the twisting device comes to halt, and the cap may be taken off from the spindle.

Depending upon the ratio of the angular velocities of the twisting member, on the one hand, and of the traveller, on the other hand, the "temporary" twist given by the twisting member 11 may be either untwisted in part (if the angular velocity of the twisting member is higher than that of the traveller) or left the same or increased through the spindle and the traveller (if the angular velocity of the latter is the same or higher than that of the twisting member), the degree of the final twist being determined in every case by the spindle and the traveller. In certain cases it is preferred to give a temporary

over-twist by means of the twisting member according to the invention to the twistable material.

In order to enable the twisting device to be correctly centered, washers 40 may be arranged between the frame 19 and the plate 18 while also the friction wheel is preferably adjustable along its shaft, in order to take up the position corresponding to the adjustment of the twisting device in that direction. The centering of the axis of the twisting member with respect to the axis of the spindle may also be effected by interposing between the rollers 12, 13, 14 twisting members of different sizes. The correct number of revolutions of the twisting member is to be adjusted also in this case by displacing the friction wheel on its shaft.

In order to obtain the most favorable angular position of the axis of rotation of the twisting member, in view of the difference of the direction of the twistable material coming from the drafting system, and that of the axis of the spindle, the angular position of the twisting device may be made adjustable about the hinge 16.

The twisting device has been shown in Fig. 11 in connection with a ring frame. The device may be obviously used in connection with other spinning frames, for instance a flyer frame too.

Although the use of the twisting device in the place of the thread guide of a spinning frame is particularly important and it has a particular technical effect in this combination, the invention is not limited to its use in connection with spinning frames.

I claim:

1. A device for imparting false twist to twistable material comprising a twisting member having substantially the form of a body of revolution and having a substantially axial passageway for the twistable material and a lateral slot extending the full length of the twisting member and forming a passage from the periphery of the twisting member to said axial passageway, said slot being inclined with reference to the axis of said member, means for rotatably supporting the twisting member, the supporting means having at least one open section affording free lateral movement of the twistable material therethrough to the twisting member when the latter is rotating at high speed, the adjacent surfaces of the twisting member and supporting means which are engaged by said twistable material when moved laterally toward and into engagement with the twisting member being inclined relative to one another so that rotation of the twisting member causes the twistable material to be taken by and moved into said slot.

2. A device for imparting false twist to twistable material comprising a twisting member having substantially the form of a body of revolution and having a substantially axial passageway for the twistable material and a lateral slot extending the full length of the twisting member and forming a passage from the periphery of the twisting member to the axial passageway, the leading edge of said slot being bevelled to permit entry of the twistable material into the slot when the twisting member is rotating at high speed, the outer periphery of the twisting member being smooth except for said slot, and means engaging the outer periphery of the twisting member for rotatably supporting said member, the supporting means having at least one open section affording free lateral movement of the twistable material therethrough to the twisting member and

supporting the twisting member with sufficient play between the outer surface of the twisting member and the supporting means so that said material can pass between said member and means without being sheared.

3. A device for imparting false twist to twistable material comprising a twisting member having substantially the form of a body of revolution and having a substantially axial passageway for the twistable material and a lateral slot extending the full length of the twisting member and forming a passage from the periphery of the twisting member to the axial passageway, and means for rotatably supporting the twisting member comprising at least three rollers rotatable on axes parallel to that of the twisting member, the rollers and twisting member having cooperating surfaces to prevent axial displacement of the twisting member at least in one direction, at least two of the rollers being spaced apart to provide between them an open space through which the twistable material can be moved laterally into contact with the twisting member to be taken by said slot and to move through said slot to the axial passageway of the twisting member.

4. A twisting device according to claim 3, in which driving means is provided for driving at least one of the rollers and thereby rotating the twisting member through frictional engagement of said roller with the twisting member.

5. A twisting device according to claim 3, in which means is provided for resiliently supporting at least one of the rollers, said roller being resiliently urged toward the twisting member.

6. A device for imparting false twist to twistable material comprising a twisting member having a peripheral surface constituting a surface of revolution and having a substantially axial passageway for the twistable material and a slot extending inwardly from the periphery of the twisting member for its full length and communicating with the axial passageway to provide a passage for lateral movement of the twistable material from the periphery of the twisting member to the axial passageway and means for rotatably supporting the twisting member comprising spaced rollers between which the twisting member is rotatably held, two of said rollers being spaced apart to provide between them a clear space through which the twistable material can be moved laterally into contact with the twisting member to be received in said slot while the twisting member is rotating at high speed and driving means for rotating the twisting member about its axis, the clear space between said two rollers being unobstructed by said driving means.

7. A device for imparting a twist to twistable material comprising a rotary twisting member having a peripheral surface constituting a surface of revolution and having a passageway for the twistable material extending through the twisting member in an axial direction and a slot extending inwardly from the periphery of the twisting member and communicating with said passageway to permit the lateral insertion of the twistable material into said twisting member, at least a portion of said slot being oblique relative to the radius of the twisting member, in a direction that causes the lag of the twistable material when inserted laterally into the twisting member rotating at high speed to move the twistable material into, and retain it in, said axial passageway, and means for rotatably supporting the twisting member, said supporting means having an opening extending the full length of the

twisting member to permit lateral insertion of the twistable material while the twisting member is rotating at high speed, the adjacent surfaces of the twisting member and supporting means which are engaged by said twistable material when moved laterally toward and into engagement with the twisting member being inclined relative to one another so that rotation of the twisting member causes the twistable material to be taken by and move into said slot.

8. A device for imparting a twist to twistable material comprising a rotary twisting member having a peripheral surface constituting a surface of revolution and having a passageway for the twistable material extending through the twisting member in an axial direction and a slot extending inwardly from the periphery of the twisting member and communicating with said passageway to permit the lateral insertion of the twistable material into said twisting member, said slot being disposed obliquely relative to the axis of the twisting member, and means for rotatably supporting the twisting member, said supporting means having an opening extending the full length of the twisting member to permit lateral insertion of the twistable material while the twisting member is rotating at high speed, the adjacent surfaces of the twisting member and supporting means which are engaged by said twistable material when moved laterally toward and into engagement with the twisting member being inclined relative to one another so that rotation of the twisting member causes the twistable material to be taken by and move into said slot.

9. A twisting device for imparting a twist to twistable material comprising a twisting member having a peripheral wall having substantially the form of a body of revolution, a slot through said wall throughout its length, said slot leading to the interior of the twisting member, a guiding eyelet at each of the opposite ends of the twisting member substantially in line with the longitudinal axis of said member, said eyelets confining the twistable material to the center of the twisting member and being open at one side to receive the twistable material, guiding surfaces for guiding the twistable material from the slot to the openings of said eyelets, a rounded surface disposed approximately midway between said eyelets and sufficiently out of line therewith to cause the twistable material to follow a non-rectilinear path from one eyelet to the other, and means for rotatably supporting the twisting member, said supporting means having an opening extending the full length of the twisting member to permit lateral insertion of the twistable material into the twisting member while the latter is rotating at high speed.

10. A twisting device according to claim 9, in which the slot is oblique with reference to the axis of rotation of the twisting member.

11. A twisting device according to claim 9, in which the eyelets are formed by rod-like members projecting inwardly from the peripheral wall of the twisting member and provided with eyes at their inner ends.

12. A twisting device according to claim 11, in which the rod-like members at opposite ends of the twisting member project inwardly from opposite sides of the peripheral wall.

13. A twisting device according to claim 9, in which the said rounded surface between the eyelets has a concave portion to receive the twistable material.

14. In a device for imparting a twist to twist-

able material, a hollow twisting member having a peripheral wall having substantially the form of a surface of revolution, a slot through said wall throughout its length, said slot leading to the interior of the twisting member, a guiding eyelet at each of the opposite ends of the twisting member substantially in line with the longitudinal axis of said member, each of said eyelets being open at one side to receive twistable material inserted through said slot, said slot being the only part on the outer surface of the twisting member that can catch and take twistable material moved laterally into contact with the twisting member when the latter is rotating in the prescribed direction, and a rounded member extending approximately diametrically across the hollow twisting member intermediate the said eyelets in a position to engage twistable material extending between the eyelets.

15. A twisting member according to claim 14, in which the slot is oblique to the longitudinal axis of said member.

16. A twisting member according to claim 14, in which said rounded member is rotatable about an axis extending transversely of the twisting member.

17. In a device for twisting twistable material, a twisting member comprising a circular spring sheet metal wall portion, two end members having portions to engage and hold the sheet metal wall portion by resilient deformation, a gap being left between the edges of the sheet metal of the wall portion to form a slot extending throughout the length of the twisting member, the end members having eyelets in their central portions and openings leading from the said slot to said eyelets and a friction member extending transversely of the twisting member between the two end members in a position to engage twistable material extending between said eyelets.

18. A device for twisting twistable material comprising a twisting member having a peripheral wall with an outer surface having substantially the form of a surface of revolution, an oblique slot through said wall, said slot extending the full length of the twisting member and opening into the interior of the said member, guiding eyelets at opposite ends of said twisting member for guiding the twistable material, each of said eyelets having a lateral opening to permit the twistable material to move laterally into the eyelet, the lateral openings of said eyelets being out of alignment with one another so that the twistable material enters one eyelet from one side and the other eyelet from another side, and means for rotatably supporting the twisting member, comprising rotatable supporting members, a space being provided between two of said rotatable supporting members for entry of the twistable material laterally into the twisting member while the latter is rotating at high speed and means for rotating the twisting member and rotatable supporting members with substantially the same peripheral speed so that the twisting member is supported by surfaces which move with it while in contact and hence without sliding friction between the twisting member and the supporting means.
